(57) **CLAIM**

The ornamental design for a goose neck foregrip, as shown and described.

DESCRIPTION

FIG. 1 is a front/right side view of the goose neck foregrip wherein the ghosted portions do not form any part of the claimed design;

FIG. 2 is a front view of the goose neck foregrip of FIG. 1;

FIG. 3 is a rear view of the goose neck foregrip of FIG. 1;

FIG. 4 is a right side elevation view of the goose neck foregrip of FIG. 1;

FIG. 5 is a left side elevational view of the goose neck foregrip of FIG. 1;

FIG. 6 is a top view of the goose neck foregrip of FIG. 1; and,

FIG. 7 is a bottom view of the goose neck foregrip of FIG. 1.
